M. L. BRUCE

TRANSMISSION BAND

Filed July 5, 1922

Murray L. Bruce

By Walter F. Murray

Attorney

UNITED STATES PATENT OFFICE.

MURRAY L. BRUCE, OF MILAN, INDIANA.

TRANSMISSION BAND.

Application filed July 5, 1922. Serial No. 572,991.

To all whom it may concern:

Be it known that I, MURRAY L. BRUCE, a citizen of the United States of America, and a resident of Milan, in the county of 5 Ripley and State of Indiana, have invented a new and useful Improvement in a Transmission Band, of which the following is a specification.

My invention relates to the type of transmission band that is used on automobiles.

An object of my invention is to provide a band of the type referred to, which may be easily, conveniently and quickly mounted about the transmission drum of a motor vehicle.

Another object of my invention is to provide a band which may be readily removed from the casing surrounding the transmission drum without dismantling the entire 20 casing.

These and other objects are attained by means described herein and disclosed in the accompanying drawing, in which:

Fig. 1 is a perspective view of a band embodying my invention.

Fig. 2 is an enlarged fragmental sectional view of the band shown in Fig. 1.

The circular band 3 comprises a single integral strip. The ends 4 and 5 of the band have substantially U shaped slits formed in them, the base of the U shaped slit extending transversely of the band, and the branches of the slits extending substantially parallel with the side edges of the band, away from the ends of the band carrying said slits. The material which is severed along three of its sides by the provision of the slits, is turned outwardly of the band and extends away from the end of the band carrying the 35 slits defining the respective severed material. This material forms lugs 6, 7, 8, and 9. The inner facing 10 of the band carries suitable lining material 11, 12 and 13. The sections of lining are spaced at their ends whereby to 40 provide ducts 14 extending transversely to the lining and the band. The lining segments are mounted on the band in any suitable manner such as by means of the two pronged rivets 15. Ears 16 and 17 are 45 mounted upon the ends 4 and 5 respectively of the band. The ears have formed in them slots 18 thru which the lugs formed on the band may be inserted. Each of the ears has

formed on it a yoke-like projection 19 between the arms 20 and 21 of which a coupling bolt 22 may extend. The coupling bolt carries the usual spring 23 and nut 24, and is adapted to be connected with suitable control levers as is common in the art. The pairs of lugs on the ends of the band are 50 spaced at such distance that each of the lugs may be inserted thru an individual slot 18 in one of the ears, and the free ends of the lugs are spaced from the band at a distance substantially equal to the thickness of the 55 ears immediately to the rear and adjacent of the slots 18 in the ears.

The ears are mounted on the band by passing the lugs thru the slots in the ears, and then moving the ears rotatively about the 60 band in directions opposite to those in which the lugs engaging the respective ears extend. The relative movements of the band and ears are continued until the rear walls 25 of the several slots 18 engage the respective lug extending thru said slots, at the forward or upper ends of the lugs, in other words, at those places where the lugs adjoin the band. In order to remove the ears from the band, the proceeding is reversed. When it is desired to remove a band embodying my invention from about the drum upon which the band is adapted to operate, either or both of the ears will be removed from the band and the band may then be rotatably actuated in 75 order to separate the band from the drum.

It should be observed that the lugs whereby the ears are mounted, constitute integral parts of the band and are so formed and struck from the band that wear upon the 80 lining and upon the band itself will not jeopardize the mounting of the ears upon the band. It should also be observed that the band comprises a single metallic strap, whereby there is no danger of separation of 85 parts as is common in transmission bands made of several hingedly connected parts.

What I claim is:

A transmission band of the class described comprising a single circular metallic band 100 having substantially U shaped lugs struck outwardly therefrom adjacent the ends thereof, the lugs being turned upon the band and extending away from the respective ends of the band carrying said lugs, and 105 ears detachably mounted on the ends of the

band having slots adapted to accommodate the lugs, the ears in mounted positions having one of the walls of each of the slots in engagement with a lug on the band, the 5 walls of the slots in the ears engaging the lugs being disposed farthest from the end of the band carrying said ear, said walls of

the slots engaging the lugs at the places of joinder of the lugs and the band.

In testimony whereof, I have hereunto 10 subscribed my name this 30th day of June, 1922.

MURRAY L. BRUCE.
